US0D1037904S

(12) **United States Design Patent** (10) Patent No.: **US D1,037,904 S**
(45) Date of Patent: ** Aug. 6, 2024

(54) **RING**

(71) Applicant: **VHERNIER S.P.A.**, Milan (IT)

(72) Inventor: **Carlo Traglio**, Milan (IT)

(73) Assignee: **Vhernier S.p.A.**, Milan (IT)

(**) Term: **15 Years**

(21) Appl. No.: **35/517,143**

(22) Filed: **Apr. 3, 2023**

(80) **Hague Agreement Data**

Int. Filing Date: **Apr. 3, 2023**

Int. Reg. No.: **DM/228590**

Int. Reg. Date: **Apr. 3, 2023**

Int. Reg. Pub. Date: **May 12, 2023**

(51) **LOC (14) Cl.** 11-01
(52) **U.S. Cl.** **D11/26**
